CLAIM

The ornamental design for a therapy pack, as substantially shown and described.

DESCRIPTION

FIG. 1a is a front plan view of a therapy pack according to the invention in which the spheres or beads are purple at a first transient temporal moment;

FIG. 1b is a front plan view thereof in which the spheres or beads are blue at a second transient temporal moment;

FIG. 1c is a front plan view thereof in which the spheres or beads are white at a third transient temporal moment;

FIG. 2a is a rear plan view thereof in which the spheres or beads are purple at a first transient temporal moment;

FIG. 2b is a rear plan view thereof in which the spheres or beads are blue at a second transient temporal moment;

FIG. 2c is a rear plan view thereof in which the spheres or beads are white at a third transient temporal moment;

FIG. 3a is a top elevation view thereof in which the spheres or beads are purple at a first transient temporal moment; FIG. 3b is a top elevation view thereof in which the spheres or beads are blue at a second transient temporal moment; FIG. 3c is a top elevation view thereof in which the spheres or beads are white at a third transient temporal moment; FIG. 4a is a bottom elevation view thereof in which the spheres or beads are purple at a first transient temporal moment;

FIG. 4b is a bottom elevation view thereof in which the spheres or beads are blue at a second transient temporal moment;

FIG. 4c is a bottom elevation view thereof in which the spheres or beads are white at a third transient temporal moment;

FIG. 5a is a left-side elevation view thereof in which the spheres or beads are purple at a first transient temporal moment;

FIG. 5b is a left-side elevation view thereof in which the spheres or beads are blue at a second transient temporal moment;

FIG. 5c is a left-side elevation view thereof in which the spheres or beads are white at a third transient temporal moment;

FIG. 6a is a right elevation view thereof in which the spheres or beads are purple at a first transient temporal moment;

FIG. 6b is a right-side elevation view thereof in which the spheres or beads are blue at a second transient temporal moment;

FIG. 6c is a right-side elevation view thereof in which the spheres or beads are white at a third transient temporal moment;

FIG. 7a is a perspective view of a therapy pack, showing the new design in which the spheres or beads are purple at a first transient temporal moment;

FIG. 7b is a perspective view of a therapy pack, showing the new design in which the spheres or beads are blue at a second transient temporal moment; and,

FIG. 7c is a perspective view of a therapy pack, showing the new design in which the spheres or beads are white at a third transient temporal moment.

The appearance of the therapy pack transitions back and forth sequentially between the appearances depicted in the a, b, and c views of each numbered figure set described above and shown. The process or period in which one appearance transitions to another forms no part of the claimed design. Purple is a claimed color in all “a” views described above and shown. Blue is a claimed color in all “b” views described above and shown. White is a claimed color in all “c” views described above and shown. The spheres or beads illustrated in the drawings are drawn so as to appear semi-transparent. The spheres or beads are non-fixed in position relative to one another. The shading lines indicate the clear or transparent nature of the therapy pack shell. Structure illustrated in broken lines is environment only and is not otherwise part of the claimed design.
